UNITED STATES PATENT OFFICE.

JOHN J. MACCREADY, OF PHILADELPHIA, PENNSYLVANIA, ASSIGNOR OF ONE-HALF TO
SAMUEL ROTHAMEL, OF PHILADELPHIA, PENNSYLVANIA.

FOLDING UMBRELLA.

No. 896,308.

Specification of Letters Patent.

Patented Aug. 18, 1908.

Application filed August 14, 1907. Serial No. 388,500.

To all whom it may concern:

Be it known that I, JOHN J. MACCREADY, a citizen of the United States, residing at Philadelphia, in the county of Philadelphia and 5 State of Pennsylvania, have invented certain new and useful Improvements in Folding Umbrellas, of which the following is a specification.

This invention relates to improvements in 10 folding umbrellas, and particularly to that class adapted to be carried by travelers.

The objects of my improvements are, to provide an entire folding frame which, when extended, shall possess all of the characteristics 15 of an ordinary umbrella, such as strength, stiffness, light weight and convenience in manipulation, and to provide such frames capable of being readily constructed and which are but slightly more expensive 20 than the ordinary frames in use.

My invention consists in the novel arrangement of parts as hereinafter fully set forth and shown in the accompanying drawings, in which,

25 Figure 1, represents an entire umbrella frame made in accordance with my invention. Fig. 2, is a partial sectional view of the telescopic handle. Fig. 3, is a sectional view of the slide runners, or sleeve. Fig. 4, 30 is a partial plan view of the lower part of the handle. Fig. 5, is a perspective view of the sliding sleeve used at the pivotal joint of the ribs.

In all the several views, similar characters 35 have been used to designate similar parts.

My invention comprises the use of an ordinary handle 1, of any preferred style or shape, which is joined by an enlarged handle section 2, to the stick 3, which may be connected by 40 any suitable means at 4, to the upper section of the stick 5, continuing entirely through the upper portion of the umbrella and terminating in a cap or point 6. Upon the upper portion of the stick 5, is secured a notch 7, 45 to which the ribs 8 are pivoted, in the ordinary manner; these ribs may be of the usual form of construction, which is generally a thin plate or strip of steel bent in a substantially "U" shaped form.

50 Midway in the length of the ribs 8, are secured sleeves 9, with depending lugs to which are secured the outer end of the brace ribs 11; in the middle of these brace ribs are pivotal

joints 12, uniting sections 13 to sections 11, in such manner that they may be folded parallel one to the other; the inner ends of all the rib sections 13, are pivotally connected to the runner 14, adapted to freely slide on the stick 5, which contains the catch 10, in the usual manner. In the frame ribs 8, and 55 beyond the connection 9, are joints 15, formed similarly to the joints 12, previously described, and connecting with the outer, or end members 16, of the umbrella frame. The pivotal joints 12 and 15, in all cases are 60 so formed as to receive a sliding sleeve 17, which when positioned over the joints renders them perfectly rigid and unyielding; in order to hold them in place when so positioned I may form the sleeves with a portion partially 65 cut away or detached, as at 17', forming semidetached portion acting in the manner of a spring, to prevent lateral displacement.

With respect to the umbrella stick, I may arrange the two sections to be connected by 70 any suitable means as indicated at 4, in Fig. 1, or I may make the sections 3 and 5, of the stick, of tubular construction and so arranged that section 3, may slide telescopically within section 5, at such times as the umbrella is 75 not in use; when, however, it is desired to extend the same, the handle portion 3, is withdrawn to the limit of the slot-way 3', terminating with a reentrant hook formed as at 3''; the runner 14, in this case, is provided 80 with a pin 14', extending inwardly and intersecting with said slot-way, in such manner that when the handle portion 3, is drawn outwardly and given a partial turn, it becomes locked in place by reason of the pin 3' 85 90 engaging with the terminations of the hooked slot-way; manifestly a reverse action disengages the stick 3, permitting it to be pushed into the upper member 5, thus it will be seen that my improved frame possesses all the 95 attributes and characteristics of high grade umbrella frames, and that it may be readily folded or collapsed, with respect to length, so that it can be conveniently carried in a suit case, trunk or other form of baggage commonly used; it will be evident that the form of joints which I use and their connections add but little weight, and are of an unobjectionable appearance; moreover that the simplicity of my invention renders the same 100 105 readily operated.

Having thus described my invention, what I claim to be new and desire to secure by Letters Patent is:

In a folding umbrella having jointed ribs, 5 of sleeves having a catch portion adapted to engage with said joints, and normally slideable on said ribs, an extensible tubular stick, the lower part adapted to slide within the upper, a runner on said stick, brace ribs connecting said runner to said ribs, a pin positioned in the runner, and adapted to engage

with a hook shaped slot in the lower stick member thereby retaining it in an extended position.

In testimony whereof I have signed my 15 name to this specification in the presence of two subscribing witnesses.

JOHN J. MACREADY.
